POWER UNIT FOR MOTOR DRIVEN TOOTHBRUSH OR THE LIKE

Donald McCarty, Long Beach, Allan B. Johnson, Tarzana,
and Michael A. Cammack, North Hollywood, Calif.,
and John W. Mattingly, John M. Trenary, and Homer
A. Jeffers, Jr., Fort Collins, Colo., assignors to Aqua
Tec Corporation, Denver, Colo., a corporation of
California

Filed Sept. 3, 1968, Ser. No. 13,357

Term of patent 14 years

Int. Cl. D4—02

U.S. Cl. D4—15

FIG. 1 is a perspective view of a power unit for motor driven toothbrush embodying our new design;

FIG. 2 is a rear side elevation of the power unit of FIG. 1;

FIG. 3 is a bottom plan view thereof;

FIG. 4 is a front elevation view thereof;

FIG. 5 is a top plan view thereof;

FIG. 6 is a righthand end elevation thereof; and

FIG. 7 is a lefthand end elevation thereof.

The dotted lines shown in the several views on the drawing are for illustrative purposes only and form no part of the claimed design.

We claim:

The ornamental design for a power unit for motor driven toothbrush or the like, as shown and described.
